UNITED STATES PATENT OFFICE.

WILLIAM T. RUTLEDGE, OF SANTA ANA, CALIFORNIA.

HOSE CLAMP.

Application filed December 10, 1923. Serial No. 679,622.

To all whom it may concern:

Be it known that I, WILLIAM T. RUTLEDGE, a citizen of the United States, residing at Santa Ana, in the county of Orange and State of California, have invented new and useful Improvements in Hose Clamps, of which the following is a specification.

This invention relates to clamping devices and more particularly to that class of clamping devices which are employed for connecting the ends of tube or hose, or in connecting the same to nipples for the purpose of forming, for example, a communication between a radiator and the water jacket of a gasoline engine.

An object of my present invention is to provide a clamp of the above character which is simple and economical and which may be quickly clamped and unclamped.

Another object is the provision of a clamp which may be adjusted without employing a nut and bolt.

A further object of this invention is to provide a clamp which is not likely to catch or pinch the hose and thereby interfere with its proper positioning and tightening.

Other objects will be appreciated upon reading the following specification.

The invention is illustrated in the accompanying drawings, in which—

Figure 1 is an elevational view, partly in section, illustrating the clamp as formed from a single band or ribbon, and means for fastening the same.

Figure 2 is an end view of Figure 1.

Figure 3 is an elevational view, partly in section, of a modified form of my invention, in which two strips or bands are employed to form the tube-enclosing ring.

Figure 4 is a side view of Figure 3.

Figure 5 is still another modification of my invention, in which the tube-enclosing ring is formed with one length of ribbon, but in which both end portions are cut away, the remaining end portions being disposed adjacent each other and extending in opposite directions and forming tongues which form a closed ring.

Figure 6 is an end view of Figure 5.

In carrying out my invention as illustrated in Figure 1 and 2, I may employ a single length of ribbon 8, having, for example, four perforations 9, 10, 11, and 12 made therein, two near each end. One end portion of the ribbon 8 may be bent at an angle at the point 13 and it may be bent

again at the point 14, and doubled back on itself forming a fold 15 and in such manner that the perforations 9 and 10 coincide with each other. The same end portion 60 may be again bent to form a loop 16 which, however, should not be closed so much as shown until the device is assembled. Not far from the other end of the ribbon 8, the latter may be bent at an angle at 17 and again at 18 and doubled back on itself to form a fold 19, so that the perforations 11 and 12 coincide, and may then be bent again at 20 beyond which point extends a tongue 21. The ribbon 8 may then be formed into 70 a ring as shown in Figure 1, the end portion of the tongue 21 underlapping the other end of the circular part of the ribbon 8, thus serving to bridge the gap between the folds 75 15 and 19.

A cotter pin 22 may be passed through the perforations 9, 10, 11, 12, after which the end of the loop 16 may be pressed down to the position shown in order to hold the head 23 of the cotter pin securely and thereby prevent the separation of the cotter pin from the ring, thus avoiding the probable loss of the cotter pin.

For the purpose of clamping the device on a hose, for example, the fold 19 may be 80 withdrawn from the lower end 24 of the cotter pin, thus allowing the device to be placed over the hose, after which the fold 19 may be passed around the end 24 of the cotter pin. The ring may then be tightened 85 around the hose by bringing together with a pliers or other means the folds 15 and 19 until the desired tightness is attained, whereupon the parts of the cotter pin may be oppositely bent and the folds of the clamp 90 thereby secured to each other, and the clamp secured to the hose.

Figure 3 is of similar construction to Figure 1 except that the tongue 21 is formed from a separate strip or band. This separate strip, as shown in Figure 3, may be secured to a portion 26 of the band 8 in any suitable manner, which may be accomplished, for example, by cutting the end 100 27 of the tongue 21 so as to provide flaps 28 and 29 which may be wrapped around the part 26 of the ribbon 8, as shown in Figure 4. Figure 3 also differs from Figure 1 in that the loop 16 is not employed.

Figure 5, like Figure 1, is formed from 110 a single band or ribbon. The differentiating feature of this form of my invention,

however, lies in the fact that there are provided two tongues, 31 and 32, respectively, which extend in opposite directions. These tongues 31 and 32 consist each of one-half of the width of the band or ribbon, being so formed by cutting away one-half of the width of the ribbon throughout their length. It will of course be appreciated that such a structure or some modification thereof is necessary in order that the tongues may pass each other in opposite directions. It will be seen that in order to effect such arrangement of the tongues the bend 14 will have to be made in a direction opposite to that shown in Figure 1.

While I have described a plurality of forms of my invention, it is evident that other modifications than those described may be readily contrived, which, however, employ the same underlying principle. For example, the folds or double layers mentioned in the specification are not essential in all forms of my invention, but are sometimes used in order to give additional rigidity. I therefore desire it to be understood that such modifications come within the scope of this invention.

I claim—

1. A hose clamp comprising a single length of ribbon bent into a ring, a portion adjacent one end of said ribbon being bent outward from the ring and bent back on itself to form a fold which is perforated, an extension beyond said fold to form a loop, a portion of the ribbon adjacent its other end bent outward and back on itself to form a perforated fold, an extension be-

yond the latter fold forming a tongue which bridges the gap between said folds, and fastening means passing through said perforations, one end of said means being secured within said loop. 40

2. A hose clamp comprising a single length of ribbon bent into a ring, a portion adjacent one end of the ribbon being bent 45 outwardly from the ring and bent back on itself to form a fold which is perforated, an extension beyond said fold bent to form a loop, a portion of the ribbon adjacent its other end bent outwardly and back on itself 50 to form a perforated fold, an extension beyond the latter fold forming a tongue which bridges the gaps between said folds, and a cotter pin passing through said perforations, one end of said cotter pin being 55 secured within said loop.

3. A hose clamp comprising a single length of ribbon bent into a ring, a portion adjacent one end of said ribbon being bent outward from the ring and bent back on itself toward the outer periphery of the ring to form a fold which is perforated, having an extension adapted to be bent upwardly away from the ring, a portion of the ribbon adjacent its other end being bent outward and back on itself to form a fold which is perforated, an extension on said ribbon forming a tongue adapted to bridge the gap between said folds, and a cotter pin adapted to pass through the perforated 70 folds for effecting a connection therebetween. 65

WILLIAM T. RUTLEDGE.
